Robt. A. Lacey

UNITED STATES PATENT OFFICE.

WALTER WARE, OF CHANDLER, MINNESOTA.

WIRE-TIGHTENER.

SPECIFICATION forming part of Letters Patent No. 373,914, dated November 29, 1887.

Application filed July 8, 1887. Serial No. 243,748. (No model.)

To all whom it may concern:

Be it known that I, WALTER WARE, a citizen of the United States, residing at Chandler, in the county of Murray and State of Minnesota, have invented certain new and useful Improvements in Wire-Tighteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of the invention is the production of a device for stretching a wire when building a fence, for tightening, loosening, and connecting a wire after the fence is built, and, finally, for joining the ends of broken wires or the ends of two wires at any place where openings are made without twisting the ends of the wire or wires together.

The invention consists in the novel features and peculiar construction and combination of parts, which will be more fully hereinafter set forth and claimed.

In the drawings, Figure 1 is a perspective view of a wire-tightener constructed in accordance with and embodying my invention, showing the operating-lever detached; Fig. 2, a perspective view showing the same in use; Fig. 3, a plan view showing the device used for connecting two ends of a wire; and Fig. 4, a perspective view of a modified form, showing an application of the same.

The windlass or drum A is provided with a series of stops or hooks *a* projected at intervals from the segment B, connected with the windlass. The hook C, located close to the windlass, curves slightly to one side of the plane of the segment B, and is adapted to catch the wire and hold it while wrapping the wire about the windlass. The hooks *a* project laterally and upwardly from the segment B, and are adapted to catch over the wire and hold the windlass when turned to the desired position. The hand-lever D is provided with a hook, *d*, close to one end, adapted to catch over the end of the segment and hold it against vertical displacement. The hook *d* projects from the rear edge of the lever and fits over and embraces the edge of the segment between

it and the lever. The edge or end of the segment is beveled, which facilitates its insertion between the hook and lever.

The lever D is detachably connected with the device, so that it can be used over and over with a number of them, and its end is extended at right angles, forming an arm or pintle, *d'*, adapted to enter the windlass, which is made tubular for the purpose, and is provided with a flange near or at its upper end to prevent the wires slipping off.

In practice, if the wire between the two posts is slack, the same can be tightened by my device, as follows: The wire is caught between the windlass A and hook C. The lever is now applied by inserting the pintle thereof in the windlass and bringing it up against the end of the segment. A continued movement will wind the wire around the windlass till slack is taken up. At this stage the wire is caught over one of the hooks *a*, whichever is nearest, and thereby prevented from unwinding. The segment does not exceed half of a circle, which in practice is sufficient, as one of the hooks thereof will be in position to catch upon the wire either upon the right or left of the windlass. When the wire is stretched too much and needs slackening, it is disengaged from the hook with which it is in engagement and the windlass is turned so the wire will unwind therefrom and be caught by another hook when the desired tension is obtained. The opening *e*, close to the windlass, is for the reception of one end of a wire which is passed therethrough and secured in any desired manner. The end of the other wire may be looped and passed over the hook C. By rotating the windlass each wire will be wound thereon and placed under tension, and when one of the wires is caught by one of the hooks the windlass will be held against back motion, as previously set forth.

The modified form shown in Fig. 4 is composed of the windlass A, the segment B', the hook *c*, the lever D', and the hook *a'*, which have their corresponding parts in the other figures. The lever D' is integral with the segment and windlass, and the hook *a'* is double and adapted to slide on the segment and rest in any one of the notches therein, which admits of a greater nicety of adjustment, as the

wire can be caught in one or the other of the two hooks.

The end of the lever D, close to or carrying the hook d, is provided with a handle extended 5 in an opposite direction to and in line with the pintle, which is grasped by the hand when operating the device.

Having thus described my invention, what I claim, and desire to secure by Letters Patent, 10 is—

1. The herein shown and described wire-tightener, composed of the windlass, the hook projected from and adapted to engage with and hold the wire close to the windlass, the segment having hooks projected therefrom for engaging with the wire and holding the windlass and segment at the desired position, and the lever, substantially as and for the purpose specified.

20 2. The combination, with the windlass and the segment having the hooks, of the lever

having a pintle fitted to the windlass, and the hook extending from the lever and fitted over and adapted to bear against the end of the segment, substantially as set forth. 25

3. The combination, with the windlass flanged at one end, the segment having the hooks a and provided with the opening e, and the hook C, located at the opposite end of the windlass, of the lever D, having handles at 30 each end and a pintle in line with and extended in an opposite direction to one of the handles and fitted in the windlass, and the hook extended from the lever and fitted over the end of the segment, substantially as and for 35 the purpose specified.

In testimony whereof I affix my signature in presence of two witnesses.

WALTER WARE.
